UNITED STATES PATENT OFFICE.

ALBERT M. BULLARD, DECEASED, BY MARION R. BULLARD, ADMINISTRATRIX, OF NEW YORK, N. Y., ASSIGNOR TO WESTERN ELECTRIC COMPANY, OF NEW YORK, N. Y., A CORPORATION OF ILLINOIS.

REVERTIVE-CALL-INDICATING MEANS FOR TELEPHONE-EXCHANGE SYSTEMS.

1,026,199.

Specification of Letters Patent.

Patented May 14, 1912.

Application filed June 4, 1909. Serial No. 500,148.

To all whom it may concern:

Be it known that I, MARION R. BULLARD, administratrix, a citizen of the United States, residing at New York, in the county 5 and State of New York, am in possession of an invention in a certain new and useful Improvement in Revertive-Call-Indicating Means for Telephone-Exchange Systems, invented by ALBERT M. BULLARD, deceased, of 10 which the following is a full, clear, concise, and exact description.

This invention relates to improved revertive call indicating means for telephone exchange systems having party lines and is 15 particularly directed toward improvements on what is shown and described in the application of Albert M. Bullard, Serial No. 355,897, filed February 5, 1907. In such a 20 system it frequently happens that a subscriber at one of the substations of a party line desires to communicate with a subscriber at another station of the same line. The ordinary busy test will in this case give a false "busy" indication, because a test 25 guard has been placed upon the multiple terminal of the line, by reason of the use of that line in calling, and not because it is already engaged by some other subscriber. It is not desirable, however, that either the 30 calling subscriber or the operator should be required to know from the mere number of the called station whether it is on the same party line as the calling station.

It is the purpose, therefore, of this invention to provide improved means for giving a special signal in all cases of such "revertive" calls, that is, where the terminal of the called line which is tested is merely a multiple terminal of the calling line. A 40 signal device is associated with the originating or answering end of the connecting circuit which is united with any calling line in response to a call, and one terminal of said signal device is arranged to be connected 45 thereby to a test conductor which extends to contacts at all the multiple terminals of such line. Testing apparatus associated with the other end of the connecting circuit is adapted to connect the other terminal of said signal device to the test conductor of the called line, so that where the terminal tested is a multiple terminal of the calling line, the circuit of said signaling device will

be completed and the signal given to indicate that the call is revertive. 65

Preferably the special signal device is brought into connection with the test conductor of the calling line only momentarily at the time of testing the called line; and at this time the usual test guard may be removed and the special revertive test circuit substituted therefor, the test guard otherwise being maintained at all multiple terminals of the line during the entire period of connection therewith. 65

This invention will be of especial utility in connection with semi-automatic systems of the type in which calls are answered by an operator and connection completed to the called line by means of automatic switching mechanism controlled by the operator. 70

The invention is illustrated in the accompanying drawing in its application to such a system. Only the circuits and apparatus which are directly concerned with the invention are illustrated, however. 75

Two lines are indicated, each having answering and connecting terminals, the former being shown as springjacks and the latter as terminals located upon an automatic selector switch. One of these lines—22—is supposed to be a party line having several stations connected therewith, while the other line—53—is of a different character, that is, it may be, for example, a trunk 80 line leading to a private branch exchange. In an automatic or semi-automatic system in which such private exchange trunk lines are provided in addition to party lines and ordinary subscribers' lines, the testing apparatus must discriminate between such trunk lines and other lines, to govern the appropriate operations of the automatic switching device which completes the connection. It is convenient to distinguish 90 private exchange trunk lines from ordinary lines or party lines by electrical potentials of different polarities applied to the test conductors, respectively, of such different classes of lines. 95

One of the features of the present invention is the provision of revertive testing apparatus which will be adapted to systems in which different classes of lines exist, one of such classes comprising lines in connection 105 with which a revertive test would not be

necessary or desirable. Means are therefore preferably provided for bringing the reductive signal device into service only when connection is made with a line of the proper 5 class, such means consisting, for example, of a polarized relay brought into connection with the test conductor of a calling line and responsive to potential of the proper polarity received therefrom.

10 In the drawing, 1, 2 and 3 represent respectively the tip, ring and sleeve of an operator's answering plug, while 4, 5 and 6 show the corresponding answering jack terminals of a subscriber's line. Associated 15 with the test conductor 7 of this line, which will be assumed to be a party line of usual construction and arrangement, is a cut-off relay 8 which is connected to the negative pole of the grounded battery 9. The character 20 of this relay 8 and its association with the subscriber's line is well known and will not be further described.

10, 11 and 12 represent respectively the tip, ring and sleeve contacts of the answering jack of a second subscriber's line, which line, however, is of a different character from that of the line already referred to, such, for example, as a private branch exchange trunk line. Associated with the 25 sleeve contact 11 of this line, by means of the conductor 13, is a cut-off relay 14 which is connected to the positive pole of the grounded battery 15. It will, therefore, be apparent that the sleeve contacts of the respective answering jacks are variously charged with a positive or negative potential, according to the character of the line with which they are associated. Both of the 30 lines referred to, however, are provided with multiple contacts 16, 17 and 18 connected respectively by the conductors 19, 20 and 21 of the tip, ring and sleeve of the various answering jacks of such lines. These multiple contacts are shown diagrammatically 35 on the right hand side of the drawing as are also shown similar contacts of other lines terminating in the exchange. When a subscriber upon the line 22, which as above noted is assumed to be a party telephone 40 line, desires connection with another party on the same line the attention of the operator is attracted in the usual way. The operator thereupon inserts the plug 23 in the jack 24 in order to receive the call. Immediately upon the insertion of this plug a test 45 guard is placed upon test conductor 21 of the calling line by means of a low resistance circuit to ground extending from the sleeve contact 6 through the sleeve 3 of the answering plug, conductor 25, contacts 26, conductor 27, low resistance winding 28 of the relay 29 to ground. This provides a path for current from the battery 9 which operates the relay 8 in the usual manner, and lowers 50 the normal potential upon the sleeve or test

contact 6 of the answering jack, and also upon the test contact 18 of the multiple contacts. It may here be noted that a circuit to maintain the cut-off relay 8 energized after its initial energization is provided, in parallel of the contacts 26 and low resistance winding 28, through the conductor 30 and the high resistance winding 31 of the relay 29, which circuit, however, since it forms no part of this invention need not be further described.

70 The operator having learned from the calling subscriber the number of the desired party causes the automatic switching device 32 at which the multiple contacts 16, 17 and 18 appear to bring its contact brushes 33, 34, 35 by any suitable means, not shown, into contact with the multiple terminals 16, 17 and 18 of the line on which the desired party is located. When this automatic switching device has made its final selective movement and the contact brushes are in contact with the multiple terminals of the desired line the switch 36 is operated by any suitable means to momentarily open the contacts 26 and close the contacts 37. This switch 36 may be arranged to be manually operated by the operator at the time desired, but is preferably arranged to be automatically operated to close the contacts 37 and 75 open the contacts 26 at the proper time by some portion of the automatic apparatus of the system with which it is associated. The movement of this switch 36 will, as will be seen, remove the test guard from the test conductor 21 of the called line by the opening of the contacts 26, so that the connector 32 in testing the line will find it in idle condition, the winding 31 of the relay 29 being of sufficiently high resistance not to reduce, 80 appreciably, the potential of the sleeve contact 6 from its normal or idle potential due to the connection of the battery 9. By the same movement of the switch 36 there is connected with the test conductor 21 through the contacts 37, conductor 25, sleeve 3, and the sleeve contact 6 of the answering jack, a high resistance circuit including conductor 38, conductor 39, polarized relay 40 and ground. This polarized relay 40 is so adjusted that it will only respond when the sleeve 3 is in contact with a sleeve contact which is negatively charged. Since the sleeve contact 6 is, however, negatively charged from the battery 9, the polarized relay 40 will be operated and close the contacts 41 controlled by the armature thereof, whereby the battery 42 will be connected to the test conductor 21 through the conductor 43, contacts 41, conductor 44, marginal relay 45, contacts 46, conductor 47, conductor 38, contacts 37 of the switch 36, conductor 25 and sleeve 3. This battery 42 is of the same polarity as the battery 9, but will be insufficient to energize the marginal relay 45 90

through the high resistance circuits provided through the polarized relay 40 and the high resistance winding 31 of the relay 29. If, however, at the time that the source 5 of current 42 and the marginal relay 45 are connected to the test conductor 21, the test brush 35 of the connecting device 32 is in contact with the multiple test terminal 18 of the calling line, which condition will exist 10 at this time if the call is a revertive one, a low resistance circuit will be established from the battery 42, including the marginal relay 45, the test conductor 21, the multiple test terminal 18, the test brush 35, conductor 15 to 48 and test relay 49 of the automatic switching device 32 to ground and back to battery. The closure of this circuit will allow sufficient current to pass from the battery 42 to energize the marginal relay 45, 20 which will thereupon attract its armature 50 and close a circuit from the battery 51 through the revertive signal 52 and ground back to battery to cause a display of this signal. The marginal relay 45 having been 25 once energized will be maintained energized by current from the battery 42 through the path including the high resistance polarized relay 40, so that the signal 52 will be maintained displayed until such time as the contacts 46 may be opened, which will occur 30 at some suitable time, either under the control of the operator or automatically in some further stage in the operation of the system.

It has been up to this time assumed that 35 the call coming in over the telephone line 22 has been a revertive one, and, as described, the signal 52 is therefore displayed. If, however, the call has not been a revertive call the final selective movement of the automatic switching device 32 will have placed 40 the contact brushes 33, 34, 35 in contact with the multiple terminals 16, 17, 18 of some line other than the calling line. No low resistance circuit over the test conductor will 45 be completed at this time for the marginal relay 45 and it will remain inert, since, as has been heretofore noted, insufficient current passes through the polarized relay 40 and the high resistance winding 31 of the 50 relay 29 to energize this marginal relay 45. The signal 52, therefore, will not be displayed.

Assuming now that a call is received over the line 53, which is of a different character 55 from the line 22, and is a line over which a revertive call is either impossible or undesirable, such a line for example as a private branch exchange trunk line. The operator as before inserts the plug 23 in the jack 54 60 in order to receive the call. When, however, after the final selective movement of the automatic switching device 32 has taken place the switch 36 is momentarily operated, the closure of the contacts 37 closes a path 65 from the positive battery 15 through the

relay 14, conductor 13, sleeve contact 12, sleeve 3, conductor 25, contacts 37 of switch 36, conductor 38, conductor 39, polarized relay 40 and ground back to battery. The current of the battery 15, however, is of the wrong polarity and will not operate the polarized relay 40, and since contacts 41 are not closed, the marginal relay 45 and the battery 42 will not be placed in operative relation to the test conductor 21 of the line 75 53, and the revertive signal can not be displayed.

The connecting circuit, which is only diagrammatically shown, since it in itself forms no part of this invention, comprises 80 as is usual the tip and ring conductors 55 and 56, respectively, induction coil windings 57, 58, 59 and 60, and the grounded battery 63 connected across the tip and ring conductors between respective windings of the 85 induction coils. The usual supervisory relays 61, 62 are also provided in the ring strand 56. The automatic switching device 32 and its associated test circuit 48 and test relay 49 are shown only so far as they are 90 necessary for full and definite understanding of this invention, and it will be, of course, understood that they may be of any ordinary or usual construction that may be desired. 95

It should be understood that in all cases where the "originating" end of the connecting circuit is referred to, either in the specification or claims, that end of the connecting circuit is meant which corresponds to 100 the answering end of an operator's cord circuit in a manual system whether such "connecting circuit" be means for interconnecting subscribers' lines in an automatic, semi-automatic or manual system. 105

Having fully described my invention, what I claim and desire to secure by Letters Patent of the United States is:—

1. In a telephone exchange system, the combination with a party telephone line 110 having multiple terminals, of a connecting circuit adapted to be united therewith, a signal device associated with the originating end of said connecting circuit, a circuit for said device independent of the talking 115 circuit, and means including multiple terminals of said party line at each end of said connecting circuit for closing the circuit of said signal device, whereby said signal device will be operated in the test of a multiple terminal of the same line to which said connecting circuit is united at the originating end. 120

2. In a telephone exchange system, the combination with a party telephone line 125 having multiple terminals and a test conductor extending to contacts at all of said multiple terminals, of a connecting circuit adapted to be united with said line at one of said multiple terminals, a signal device 130

adapted to be temporarily associated with said line by said connecting circuit, and means for closing a circuit for said signal device through said test conductor and corresponding multiple contacts of said connecting circuit at each end thereof, whereby said signal device will be operated when said connecting circuit is connected at both ends to the same line.

10 3. In a telephone exchange system, the combination with a party telephone line having multiple terminals, of a connecting circuit adapted to be united with said terminals, a signal device associated with the

15 originating end of said connecting circuit, a circuit for said signal device independent of the talking circuit and including multiple terminals of said party line at each end of said connecting circuit, and a switch

20 in said circuit momentarily operated to close the circuit of said signal device, whereby said signal device will be operated by the closure of said switch when said connecting circuit is connected at both ends to the same line.

25 4. In a telephone exchange system, the combination with a party telephone line having multiple terminals, of a test conductor extending to contacts at all of said

30 multiple terminals, a connecting circuit adapted to be united with said multiple terminals, a signal device associated with the originating end of said connecting circuit, a circuit for said signal device independent

35 of the talking circuit and including said test conductor and contacts at each end of said connecting circuit, and a switch in said circuit momentarily operated to close the circuit of said signal device, whereby

40 said signal device will be operated by the closure of said switch when said connecting circuit is connected at both ends to the same line.

45 5. In a telephone exchange system, the combination with a party telephone line having multiple terminals, of a connecting circuit adapted to be united therewith terminating in an automatic switching device, one of said multiple terminals being located

50 in said switching device, test means associated with said switching device, a signal device, a circuit for said signal device including said test means and contacts of said multiple terminals at both ends of said connecting circuit, and a switch for closing the

55 circuit of said signal device, whereby said signal device will be operated by the closure of said switch in the test of a multiple terminal of the same line to which said connecting circuit is united at its originating end.

60 6. In a telephone exchange system, the combination with a party telephone line having multiple terminals, of a connecting circuit adapted to be united therewith termi-

nating in an automatic switching device, one of said multiple terminals being located in said switching device, test means associated with said switching device, a signal device, a circuit for said signal device independent of the talking circuit including said test means and contacts of said multiple terminals at both ends of said connecting circuit, and a switch for closing the circuit of said signal device, whereby said signal device will be operated upon the closure of said switch, when said connecting circuit is in contact at both ends with multiple terminals of the same line.

70 7. In a telephone exchange system, the combination with a party telephone line having multiple terminals, of a test conductor extending to contact at all of said multiple terminals, of a connecting circuit adapted to be united with said multiple terminals terminating in an automatic switching device, one of said multiple terminals being located in said switching device, test means associated with said switching device, a signal device, a circuit for said signal device including said test conductor and said test means, and a switch for closing the circuit of said signal device, whereby said signal device will be operated upon the closure of said switch, when said connecting circuit is in contact at each end with multiple terminals of the same line.

75 8. In a telephone exchange system, the combination with a party telephone line having multiple terminals, of a test conductor extending to contacts at all of said multiple terminals, some of said terminals being located upon automatic switching devices, an answering switch adapted to make contact with the line when calling, a signal device adapted to be connected to said test conductor by said answering switch, an automatic switching device to which connection may be extended from said line through said answering switch, said switching device having access to one of the multiple terminals of said lines, and testing apparatus associated with said switching device to complete a circuit for said signal device through the test conductor of the line, whereby said signal device is operated when the line tested by the automatic switching device is the calling line.

80 9. In a telephone exchange system, the combination with a party telephone line having multiple terminals, of a connecting circuit adapted to be united therewith, means associated with said connecting circuit for placing a test guard upon said party line, a signal device, a circuit for said signal device independent of the talking circuit and including said multiple terminals at both ends of said connecting circuit, and means for removing said test guard and closing the circuit of said signal device.

10. In a telephone exchange system, the combination with a party telephone line having multiple terminals and a test conductor extending to a contact at all of said 5 multiple terminals, of a connecting circuit adapted to unite with said multiple terminals, means associated with said connecting circuit for placing a test guard upon said party line, a signal device, a circuit for said 10 signal device including the test conductor of said party line and multiple contacts thereof, and means for removing said test guard and closing the circuit of said signal device.

11. In a telephone exchange system, the 15 combination with telephone lines of different character terminating in an exchange, a connecting circuit arranged to be connected with a calling line, a signal device, a circuit for said signal device including contacts associated with said calling line at both ends of said 20 connecting circuit, and means for closing said circuit operated if the calling line is of a particular character.

12. In a telephone exchange system, the 25 combination with telephone lines of different character terminating in an exchange, a connecting circuit arranged to be connected with a calling line, a signal device, a circuit for said signal device independent of the talking 30 circuit and including contacts associated with said calling line at both ends of said connecting circuit, and means for closing said circuit operated if the calling line is of a 35 particular character.

13. In a telephone exchange system, the 40 combination with telephone lines of different character terminating in an exchange, a connecting circuit arranged to be connected with a calling line, a signal device, a circuit for said signal device including the test conductor of a calling line and multiple contacts thereof, and means for closing said circuit operated if the calling line is of a 45 particular character.

14. In a telephone exchange system, the 45 combination with telephone lines of different character terminating in an exchange and having multiple terminals, a connecting circuit adapted to be united with said multiple 50 terminals, a circuit associated with said connecting circuit arranged to be connected to the test conductor of a calling line, electromagnetic means in said circuit arranged to be operated when the line with which said circuit is connected is of a particular character, a signal device under the control of said electromagnetic means, a circuit for said 55 signal device including multiple terminals of the calling line at both ends of said connecting circuit, and means for closing the 60 circuit of said signal device.

15. In a telephone exchange system, the combination with a party telephone line having multiple terminals, a test conductor extending to contacts at each of said multiple terminals, a source of current connected to said test conductor, a connecting circuit adapted to be united with said line at one of said multiple terminals, a second source of current of the same polarity as said first 70 mentioned source of current, means for connecting said second source of current to said test conductor at the originating end of said connecting circuit, a signal device, test means associated with said connecting circuit adapted to test the desired line, and a circuit for said signal device including said second source of current, said test conductor 75 and said test means.

In witness whereof, I hereunto subscribe 80 my name this second day of June, A. D. 1909.
